UNITED STATES PATENT OFFICE.

WILLIAM R. McFETRIDGE, OF PITTSBURGH, PENNSYLVANIA.

RAIL JOINT.

Application filed February 20, 1925. Serial No. 10,664.

To all whom it may concern:

Be it known that I, WILLIAM R. McFETRIDGE, a citizen of the United States, residing at Pittsburgh, in the county of Allegheny and State of Pennsylvania, have invented certain new and useful Improvements in a Rail Joint, of which the following is a specification.

This invention relates to improvements in rail joints.

The primary object of this invention is the provision of a boltless rail joint, adapted to be used for the splicing of rail sections in a positive, adjustable, and efficient manner, so that the rail sections may respond to normal expansion and contraction, and are prevented from lateral play.

A further object of this invention is the provision of rail section clamping means to be used at the joint, whereby the rail sections are connected together against lateral play, by means of a boltless clamp structure, which embodies novel means for quickly adjusting the clamping action.

A further and important object of this invention is the provision of a boltless rail clamp, which is particularly well adapted to be used in connection with the boltless connection of rail sections, in an efficient and expeditious manner; the invention being particularly desirable for use with tracks which are temporary, and have to be taken up and laid from time to time, as is the case with mine tracks, temporary sidings, and the like.

A further object of this invention is the provision of an improved rail joint, which is boltless in its action of splicing rail sections together, and which comprises a novel type of bed plate formed to cooperate with wedge members which secure the rail to the bed plate in a reinforced condition against lateral play.

Other objects and advantages of this invention will be apparent during the course of the following detailed description.

In the accompanying drawings, forming a part of this specification, and wherein similar reference characters designate corresponding parts throughout the several views,

Figure 1 is a plan view showing the man-

ner in which the improved rail joint or clamp is used for securing aligning sections of a rail upon the ties of railway bed.

55

Figure 2 is a plan view showing certain cooperating details of the improved rail joint, prior to assemblage of the complete structure.

Figure 3 is a cross sectional view taken 60 through the improved rail joint substantially on the line 3—3 of Figure 1.

Figure 4 is a side elevation of a novel type of wedge plate which is used in connection with the securing of the rail sections 65 together and to a base plate.

Figure 5 is a fragmentary plan view of a modified form of improved rail joint, embodying features common to the form of invention illustrated in Figure 1.

70

Figure 6 is a perspective view showing the tie or base plate of the improved joint structure with a novel type of clamp plate cooperatively connected thereto.

75

Figure 7 is a cross sectional view taken 75 through the improved rail joint in assembled position, substantially on the line 7—7 of Figure 5.

In the drawings wherein are shown preferred and modified forms of the invention, 80 the letters A and B may designate rail sections adapted to be connected by the rail joint structure C upon and between the ties D.

Referring to the preferred form of rail 85 joint C, the same preferably comprises a base plate 10, and wedge or side plates 11 and 12. The rail sections A and B are standard, and comprise the base 14; centrally disposed vertical web 15; and head 90 16. At the juncture of the side surfaces of the web 15 with the bottom tapered surfaces 18 of the rail head 16, the conventional fillets 19 are provided, having the concaved surfaces 20, and which are important in 95 that the wedge plates 11 and 12 are received thereagainst to effect the rail splice, as will be subsequently described.

As to the base plate 10, the same in the preferred instance is constructed of steel 100 plate material, which may vary in quality, size, and other characteristics to suit the weight and dimensions of the rails with which it is to be used. However, this base

plate 10 preferably comprises the flat body portion 25, of rectangular formation, which at the longitudinal or side edges thereof is provided with the upturned and inwardly inclined overhanging flanges 26 and 27, which provide pockets or grooves 28 extending longitudinally at the side edges of the base plate, and which pockets or grooves 28 are open at the end edges 30 of said base plate 10. The overhanging upturned flanges 26 and 27 are inclined at an angle of preferably 45° , and the bottoms of the grooves or pockets 28 are preferably concavely arcuate, to cooperate in providing an efficient construction upon which the wedge plates 11 and 12 may slide, as will be subsequently described. Thus, the retaining flanges 26 and 27 are disposed in an upwardly converging relation towards the head of the rail 20 adapted to be supported upon the bed plate.

The base plate 10 inwardly of the retaining flanges 26 and 27 is preferably provided with the spaced upwardly bent rail base attaching flanges 30 and 31, which are struck from the material of the body 25. During fabrication or prior to formation of the rail joint these attaching flanges 30 and 31 are disposed in a vertical plane, and they are spaced just sufficiently to permit the base of the rail to be slipped therebetween, so that the side edges of the rail base engage the same. The said attaching flanges 30 and 31 after assemblage of the rail base therebetween may be bent over, or hammered over the base flange of the rail in any approved manner, substantially as is illustrated in Figures 2 and 3 of the drawing. Any approved number of these rail attaching flanges 30 and 31 may be provided at each side of the rail base, although as is illustrated in Figure 2 two pairs of attaching flanges 30 and 31 for each of the rail sections A and B are provided. A single pair of attaching flanges 30 and 31 may be provided at the juncture of the rail sections A and B, if found expedient. Contemporaneous with the stamping of the base plate to provide the attaching flanges 30 and 31, it is preferred to provide vertical openings 35 contiguous with the said attaching flanges into which the shanks of rail base attaching spikes 36 may be driven, substantially as is illustrated in the drawings.

Referring at this time to the assemblage of the improved type of rail joint C, the base plate 10 is preferably of sufficient length that the ends thereof may rest upon adjacently spaced ties D. With the attaching flanges 30 and 31 vertically disposed the plate portions of the rail sections A and B are lowered or slipped therebetween, and when the end edges of the said rail sections have been spaced or placed in the desired abutting relation, the spikes 36 are driven through the openings 35 into the ties D, and the attaching flanges 30 and 31 are bent over

the opposite edges of the rail base flange 14, which securely connects the rail sections to the base plate and to the bed ties D.

Referring to the side or wedge plates 11 and 12, the same are of similar construction, and are flat in the form of a trapezoid. These wedge plates are preferably of the same length as the base plate 10, although they may be longer or shorter if desired, and each of the same includes the straight edge 40 which is transversely convexly arcuated, and which is arranged in a line at right angles to the straight end edges 41 and 42. The opposite straight edge 43, which longitudinally extends at the opposite side of the wedge plate from the longitudinal straight edge 40 is disposed in a converging relation with the straight edge 40, and this edge 43 is transversely convexly actuated or rounded.

The side or wedge plates 11 and 12 serve as wedges when driven into place, and these plates are positioned at opposite sides of the rail within the grooves or pockets 28 formed by the retaining flanges 26 and 27, with the upper edges thereof disposed in a sliding relation against the fillets 19 beneath the rail head 16. Since these wedge plates have a width which uniformly varies from end to end, and are rounded at their longitudinal edges, to render them non-cutting, they may be readily forced into the position mentioned, and locked therein incident to their wedge action. The plates 11 and 12 are driven into place from opposite ends of the base plate, as is illustrated in Figure 1 of the drawings, to render the wedging action more efficient in the functions of reinforcing and locking the rail joint. As is illustrated in Figure 1 the primary wedging action 105 preferably leaves the driving ends of the wedge plates 11 and 12 slightly protruding from the end edges of the base plate 10, so that at any future time if the rail joint is loosened, as to permit lateral play or vibration of the rail sections, the same may be tightened merely by a trackman hitting the protruding ends of the wedge plates to tighten the rail joint. The wedging action is accomplished because of the action of the 115 wedge-shaped side plates between the grooves of the base plate and the surfaces formed at the juncture of the rail web and head, since the spacing of these grooves and surfaces is constant throughout the length of the base plate. The wedge plates may be easily driven into place, and are prevented from return movement by their frictional engagement with the rail sections. If, however, it is found that vibration loosens the 125 wedging action, stop devices may be placed at the protruding ends of the wedge plates to maintain the wedging position. This is merely a refinement and has not been illustrated in the drawings. The taper of the 130

edge 43 with respect to the edge 40 may vary, but for efficient purposes has been found to comprise a taper of $\frac{1}{4}$ " in 20". When in place the wedge plates are disposed 5 at an angle of substantially 45° , and they are locked in place against any lateral movement.

In the form of rail joint C it is contemplated to construct the base plate 10 and side 10 plates 11 and 12 of steel plate material. However, it is recognized that under certain circumstances of use it may be desirable to form the rail joint base plate of cast material, and in this case special steel plate attaching means for connecting the cast bed plate to the rail will have to be provided. Such a construction is provided by my improved rail joint E, which comprises a cast 15 bed plate 50; cast wedge plates 51 and 52; and a steel clamping plate 53. The rail joint E is adapted to be used with heavy steel rails, and the section G and H thereof have parts which are numbered identical with the parts of the sections A and B in Figure 1 of 20 the drawings. The wedge plates 50 and 51 are of identical wedging construction with the plates 11 and 12 of the form of rail joint 25 C, and the same characteristics feature in the plates 50 and 51 as have been given the wedge plates 11 and 12. The wedge plates 50 and 51, however, are preferably cast, and are thicker than the wedge plates 11 and 12.

The cast base plate 50 comprises the flat body portion 55, having the upwardly converging longitudinal side flanges 56 and 57 overhanging slightly the body 55, to provide the longitudinal inwardly facing pockets or grooves 59 and 60 adapted to receive the lower edge portions of the wedge plates 51 35 and 52, in the manner above described for the rail joint C. The base plate body 55 is preferably provided with a pair of parallel longitudinally extending slots 61 and 62, substantially midway of the ends of the base plate 50, which are spaced so that when the rail is applied the vertical slots 61 and 62 will extend upwardly flush with the outer 40 marginal edges of the rail base flange 14.

The steel clamping plate 53 is preferably 45 of stock material, and is bent into a U-shaped formation to provide a connecting body portion 65 which lies beneath the base plate body 55, and furthermore includes the upwardly extending end attaching flanges 67 and 68 which are adapted to project upwardly through the slots 61 and 62 respectively. The attaching flanges 67 and 68 after they have been assembled in the relation illustrated in the dotted lines in Figure 7 of the drawing have their upwardly projecting ends flanged over, at 70, into overlapping abutting and locking engagement with the rail flange 14, to lock the rail to the base plate. It is to be particularly noted that the clamping plate 53 is

applied between the road bed ties D, so that the same may be not interfere with the laying of the base plate 50 at its ends upon said ties D. The operating features of the rail joint E, other than the attaching plate 70 53 are the same as for the form of rail joint C, and the body 55 of the base plate 50 is provided with vertical passageways 68^a therein for receiving the attaching spikes 69.

From the foregoing description of this 75 invention it is apparent that a novel type of rail joint has been provided, which is used in a novel boltless manner for the effective securing of rail sections together. The joint does not necessitate the punching of the 80 rail webs for splice bolts, and does not interfere with other construction of the ties or rail sections. The rail joint is simple to construct, comprising parts which may be economically fabricated, and it embodies 85 a novel adjusting feature by which the rail sections may be tightened at the joints, from time to time, should any play be occasioned by reason of vibration; this adjustment being secured by merely movement of the wedge plates in the manner above described into the base plate.

Various changes in the weights and dimensions, as well as alterations in the shape and arrangement of parts may be made to the base plates, wedge plates, and clamping features of the forms of this invention, to conform to the circumstances and the type of rail with which the improved rail joints 95 are being used, without departing from the spirit of the invention or the scope of the claims.

I claim:

1. As an article of manufacture a base 105 plate for rail joints comprising a flat body portion having upwardly extending bendable attaching flanges formed in laterally spaced relation therein and inwardly of the longitudinal edges thereof.

2. As an article of manufacture a base 110 plate for rail joints comprising a flat body portion having upwardly extending bendable attaching flanges formed in laterally spaced relation therein and inwardly of the longitudinal edges thereof, said base plate at the opposite longitudinal edges thereof having upwardly extending and inwardly inclined retaining flanges providing inwardly facing grooves opened at the ends of said base plate.

3. As an article of manufacture a wedge 115 plate for rail joints comprising an elongated flat metal plate having the opposite longitudinal edges thereof disposed in a converging relation from one end of the plate to the other so that the same varies in width from one end to the other, said converging longitudinal edges being convexly arcuated in cross section to provide non-cutting edges.

4. In a rail joint the combination with

a rail including a base, a web and a head, a base plate beneath the rail having attaching flanges extending upwardly in spaced relation on the base to secure the rail to the base plate, said base plate providing laterally extending portions at opposite sides of said base of the rail, said laterally extending portions having upwardly extending retaining flanges to provide longitudinal 10 inwardly facing grooves open at the ends of the base plate, and wedge plates adapted to be driven into said grooves in upwardly converging relation in engagement beneath the heads of said rails to wedge the rail and base plate into locking engagement.

5. In a rail joint the combination with a rail including a base, a web and head, a base plate beneath the rail having attaching flanges extending upwardly in spaced relation on the base to secure the rail to the base plate, said base plate providing laterally extending portions at opposite sides of said base of the rail, said laterally extending portions having upwardly extending retaining flanges to provide longitudinal inwardly facing grooves open at the ends of the base plate, wedge plates adapted to be driven into said grooves in upwardly converging relation in engagement beneath the head of said rail to wedge the rail and base plate into locking engagement, and spikes for securing the rail through the base plate to ties beneath the base plate.

6. In a rail joint construction the combination with a pair of rail sections and railway ties, a base plate seated upon said ties in bridging relation therebetween, said base plate having upwardly extending attaching flanges in laterally spaced relation thereon, said rail sections being adapted to be placed upon said base plate with the attaching flanges at opposite sides of the base of the rail sections, said base plate having laterally extending portions at opposite sides of the rail sections providing grooves inwardly facing towards said rail sections, spikes securing the rail sections to the base plate and to the ties, and wedge plates slidably inwardly at opposite ends of the base plate between the longitudinal pockets thereof and the heads of the rail sections.

7. In a boltless rail joint the combination with a rail including a base, a web, and an enlarged head, a base plate of a width greater than the width of the rail base and extending laterally at opposite sides of the rail base, said base plate having upwardly extending and inwardly inclined retaining flanges providing longitudinal grooves opening at the ends of the base plate, means securing the base plate to the rail, and upwardly converging wedge plates extending from abutment in the grooves of said retaining flanges to abutment at the juncture of the head and web of said rail, said wedge

plates being adapted to be driven inwardly at opposite ends of the base plate into locking wedging engagement between the retaining flanges and rail head.

8. In combination with a rail section and a railroad tie, a base plate mounted on the tie having the rail section mounted thereon, said base plate at the side edges thereof having retaining flanges extending beyond the lateral edges of the rail section, spike means connecting the rail section to the ties and the base plate, and wedge plates formed to be driven into wedging relation between the retaining flanges and rail section is non-interfering relation above the spikes.

9. In combination with a rail section and a railroad tie, a base plate mounted on the railroad tie, said rail section being disposed on the base plate, said base plate being wider than the rail section and laterally of the sides of the rail section having upwardly extending attaching flanges of a bendable nature adapted to be bent over into securing relation upon the rail section to fixedly attach the same against relative movement with respect to the base plate, said base plate furthermore having side retaining flanges laterally of the attaching flanges above mentioned, spike means securing the rail section and base plate to the tie, and wedge plates adapted to be diagonally positioned in wedging relation between the rail section and retaining flanges at opposite sides of the rail section and above said spike means in a non-interfering relation therewith.

10. In a rail securing means the combination with a rail section and a railroad tie, a base plate adapted to rest upon the tie and to have the rail section rest thereon, said base plate inwardly of the side edges thereof having upwardly struck attaching flanges of a bendable nature adapted to be bent into securing relation over the rail section, said base plate laterally of said attaching flanges having grooved retaining flanges at opposite sides of the rail section, spike means securing the rail section and base plate to the tie, said spike means including heads, and wedge means between the rail section and retaining flanges at opposite sides of the rail section for wedging the rail section in stable position upon the base plate.

11. In means for attaching rails to ties the combination with a tie and a rail section, a base plate adapted to rest on the tie, and to have the rail section rest thereon, said base plate being wider than the rail section, said base plate having openings therein, spikes driven thru the openings into the tie and having the heads thereof engaging the base of the rail section to hold the base plate and rail section in secured relation upon the tie, said base plate laterally of the spikes having side retaining flanges extend-

ing along the sides of the rail section in spaced relation with the base of the rail section and flat wedge plates disposed at opposite sides of the rail section in a converging relation each engaging at a lower edge thereof in a retaining flange of the base plate and therefrom extending diagonally

upward into engaging relation at its upper edge beneath the head of the rail section, said wedge plates when so positioned being entirely disposed above the heads of the spikes in a non-interfering spaced relation therewith. ¹⁰

WILLIAM R. McPHERTRIDGE.
